United States Patent Office.

SAMUEL EASTER, OF CHARLESTOWN, MASSACHUSETTS.

Letters Patent No. 93,425, dated August 10, 1869.

IMPROVED SASH-LOCK.

The Schedule referred to in these Letters Patent and making part of the same.

To all whom it may concern:

Be it known that I, SAMUEL EASTER, of Charlestown, in the county of Middlesex, and State of Massachusetts, have invented a new and useful Lock for Fastening Windows, &c.; and I hereby declare that the following is a full and exact description thereof, and reference may be had to the accompanying drawings, and to the letters of reference thereon, making part of this specification, of which—

Figure 1 is a vertical section of the lock, and the window-pane and sashes connected therewith.

Figure 2 is a horizontal section of the same.

Figure 3 is a top view of the lock.

Figure 4 is a vertical section of the lock.

Figure 5 is a view of the top of the lock, with the outer plate removed.

The letter A represents the window-frame.

B C, the sashes.

D, the bar, supporting the lock.

a b, the bolts of the lock.

c, its case.

d d, its springs.

e, the recess in the bolt-bar f, for the pallet g to work in.

h, the shaft, for turning the pallet back and forth.

i i i, &c., notches or holes in the sashes to receive the bolts.

The window-frame, sashes, &c., are made in the usual way, and the sashes have notches or holes, as i i i, &c., as seen in figs. 1 and 2 in the accompanying drawings, and these notches correspond in the sashes, so that the same may be made fast, and neither be raised or lowered without a turn of the lock.

Fig. 2 shows the position of the sashes when made fast, whether the window is closed or open, at top or bottom, or both top and bottom. There may be, also, a slot or groove in the sashes, allowing them to be raised or lowered a short space. The lock is a simple but effective device.

Fig. 3 shows the lock as it appears when the bolts a b are pushed into the sashes B C, as seen in fig. 2, and also the shaft for turning the pallet.

Fig. 4 is a vertical section of the lock, showing the bolt b, the pallet g, which is made fast to the shaft h, the case c, and the recess e.

Fig. 5 shows the interior of the lock, the springs d d, the recess e, and the pallet g.

The lock is made of metal, consisting of an outer

plate inserted and fastened into the face of the frame, as seen in fig. 1, with the back set in, as seen in said figure.

The lock is one inch in depth, from the front plate, or thereabout. The front plate and top of the case, c, are in one piece. The case, except the top, is in one piece, and the shaft h and pallet g are secured to and therein, as seen in fig. 3.

The bolts a b are in one piece, with pins in the back part of each bolt, which keep in place the springs d d; the springs push against the back of the case of the lock.

The recess e in the bar-bolt is made flaring on the side toward the shaft h, so that when the pallet g is pushed back and forward, it locks and holds the bolt in place, locked or unlocked.

The shaft h pierces the front of the casing, and is turned back and forth with a key. When the bolts are turned back by the key, they remain fast in that position, and when the window is raised or lowered and the bolts locked, they cannot be raised or lowered again without turning the key. The window can be let down from the top and be made fast, so that no one from without or within can raise or lower it without the use of the key, and no one from without can pick the lock or raise the window, thus making it secure.

The device of the lock is simple in construction, costing less than the usual fastening when the windows are closed; it is as effective in securing the window as any device can possibly be, and will be of great value in almost any kind of window of more than one sash.

I do not claim, broadly, the use of the spring bolt for the purpose of supporting and securing the upper and lower sash of windows; nor do I claim, broadly and severally, the devices hereinbefore described for shooting the bolt; but

I claim, and desire to secure by Letters Patent—

The combination and arrangement of the flaring recess e, the bolt-bar c, the shaft h, pallet g, by means of which the bolts a b are actuated and secured in position either when projected or withdrawn.

SAMUEL EASTER.
